CLAIM

The ornamental design for a part for parasol, as shown and described.

DESCRIPTION

FIG. 1 is a top perspective view of a part for parasol showing our new design;

FIG. 2 is a front elevation view thereof;

FIG. 3 is a rear elevation view thereof;

FIG. 4 is a right elevation view thereof;

FIG. 5 is a top view thereof;

FIG. 6 is a bottom view thereof;

FIG. 7 is an enlarged detail thereof taken from an in-use elevation view; and,

FIG. 8 is an enlarged detail taken in the direction of arrows 8-8 of FIG. 7.

The broken lines showing a parasol represent environmental structure that forms no part of the claimed design.

1 Claim, 7 Drawing Sheets
